THREAD CUTTING MACHINE

Mark W. Anthony, Houston, Tex.

Application September 25, 1937, Serial No. 165,695

5 Claims. (Cl. 82—36)

This invention relates to a thread cutting machine.

An object of the invention is to provide a machine of the character described specially designed for cutting threads and has particular relation to novel means for adjusting the cutter bar with relation to the work.

An object of the invention is to provide a thread cutting machine having a cutter mounted thereon with novel means for adjusting the cutter bar whereby the cutter may be applied under the exact control of the operator.

The machine is specially useful, not only for the purpose of cutting threads, but for the purpose of facing the threads whereby to produce a smooth, nice finish to the threads.

With the above and other objects in view, the invention has particular relation to certain novel features of construction, operation and arrangement of parts, an example of which is given in this application and illustrated in the accompanying drawings wherein:

Figure 1 shows a plan view of the device shown partly in section as applied to the work.

Figure 2 shows a vertical sectional view taken on the line 2—2 of Figure 3.

Figure 3 shows an end elevation showing the lathe carriage in section.

Figure 4 shows an end view, showing the end opposite that shown in Figure 3.

Figure 5 shows a cross sectional view taken on the line 5—5 of Figure 2.

Figure 6 shows a fragmentary plan view partly in section, taken on the line 6—6 of Figure 3, and

Figure 7 shows a fragmentary side elevation partly in section of the cutter bar illustrating another embodiment.

Referring now more particularly to the drawings wherein like numerals of reference designate the same parts in each of the figures, the numerals 1 and 2 designate the end members of the framework which have the aligned bearings 3 and 4 respectively, in the latter of which there is mounted a bushing 5 preferably formed of brass or bronze or similar material. This bushing is split as shown in Figure 3. The end members 1 and 2 are mounted on a lathe carriage 6 which has the longitudinal dovetailed groove 7. In the groove are the anchor blocks 8, 8 and bolts 9, 9 have their heads countersunk into said blocks and extend upwardly through said end members and have the nuts 10, 10 threaded onto the upper ends thereof. When it is desired to adjust the end members the nuts 10 may be loosened and the adjustment made and then

again tightened whereby the blocks 8 will be drawn into clamping relation with the carriage as shown in Figure 3. As clearly illustrated in Figures 3 and 4 the end members 1, 2 have the depending legs 11, 11 which fit snugly into the 5 groove 7.

The bearings 3, 4 are in alignment. There is a cutter bar 12 fitted snugly in the bearing 3 at one end and its other is reduced and fitted through the bushing 5 as shown in Figure 2. The 10 bearings 3, 4 are split, as illustrated in Figures 3 and 4. There are the clamp bolts 13, 13, whose inner ends have threaded connections with the end members and whose outer ends are threaded to receive the clamp nuts 14, 14. These 15 clamp bolts extend across the split sides of said end members and by tightening up on the nuts 14, the bearings may be adjusted to fit snugly about the cutter bar 12. One end of the cutter bar has a transverse bearing 15 therethrough to 20 receive the bit, or cutter, 16. A clamp rod 17 extends axially through the bar 12. One end of the clamp rod bears against the cutter 16 and threaded into the other end of the bar 12 there is a clamp screw 18 whose inner end abuts the 25 opposing end of the clamp rod 17 whereby said rod may be held in clamping relation with the cutter 16 or released.

That portion of the bar 12 between the end members 1, 2 is provided with the external 30 threads 19. Surrounding said threaded portion and located between said end members there is the adjusting sleeve 20 which has a threaded connection with the threads of the bar 12. The mid-portion of the sleeve 20 is thickened outwardly as more clearly shown in Figure 2 and is provided with spaced, radial sockets 21 to receive the inner end of the grip member 22 which may be inserted into one of said sockets for turning the sleeve 20 and thereby adjusting the bar 12 40 longitudinally. The ends of the sleeve 20 are reduced in diameter and around said reduced ends are the antifriction bearing assemblies formed by the outer and inner raceway rings 23, 24 and the antifriction bearings 25 between 45 them, thus forming antifriction mountings for the sleeve 20. These bearing assemblies are confined between the end member 1 at one side and the annular bearing plate 26 at the other side. Adjusting screws 27 are threaded through the 50 end member 2 and their inner ends bear against the plate 26 whereby the bearing assemblies may be adjusted to take up for wear. The elevated, or outwardly thickened portion of the sleeve has 55 graduations 28, as shown in Figure 1 and fastened

on the end member 1 there is a pointer 29 arranged to cooperate with the graduated portion of the sleeve 20. The sleeve 20 has an inside longitudinal groove 30 in which there is located 5 a jaw 31, whose inner face is threaded to mesh with the threads 19. A screw 32 is threaded radially through the sleeve 20 with its inner end bearing against the jaw 31. The clamp screw 32 may be tightened up against the jaw 31 from time to time to take up the wear between the threads of the bar 12 and the sleeve 20.

Around the outer end of the bar 12 there is a collar 33. It is keyed against rotation, relative to the bar, by means of the key 34 which is held against displacement by means of a clamp screw 35, which is threaded radially therethrough and whose inner end clamps against the key 34. This collar 33 has a bearing 36 therethrough and a guide rod 37 has its inner end suitably 20 anchored to the end member 1 and its outer end extends through the bearing 36 as shown in Figure 2 whereby the bar 12 is held against turning while it is being longitudinally adjusted.

In operation, the machine may be applied to 25 the work as 38a. As illustrated in the present instance the work 38a consists of a collar or coupling which is internally threaded. The work may be mounted in and turned by the lathe and the thread cutter 16 fed thereto by the usual 30 lathe manipulations. After the threads have been cut it is then often desirable to smooth the sides of the threads. The machine is shown, in Figure 1, as applied to the work of smoothing the sides of the threads that have previously 35 been cut. In order to do this work, the bar 12 must be adjusted longitudinally so as to bring the point, or cutting edge, of the cutter 16 into cutting relation with the side of the threads to be smoothed. This requires nice adjustment. It 40 is accomplished by turning the sleeve 20 by use of the handle 22 until the required adjustment has been made. The adjustment will be indicated by pointer 29 with relation to the graduations 28. When one side of the thread has been smoothed 45 throughout, the bar 12 may then be adjusted in a similar manner in the other direction so as to bring the cutting edge in cutting relation with the other side of the thread and said other side of the thread faced off or smoothed. This will 50 leave the trough between the threads incomplete or unfinished as illustrated in Figure 1. The bar 12 may then be adjusted to bring the cutter exactly midway between the threads and the lathe then manipulated to cause the point 55 of a cutter to cut out or finish the trough between the threads and thus complete the work.

A cutter bar 12a as shown in Figure 7 may be substituted for the bar 12 shown in the other figures, by removing the bushing 5 and making 60 the substitution. On the bar 12a is the outwardly threaded sleeve 38 which may be adjusted to the desired point on said bar. This sleeve may be held at any point of adjustment by a set screw 39 whose inner end projects into a corresponding 65 recess 40 in the bar 12a. A number of recesses 40 are provided which are spaced apart along said bar, thus providing for different points of adjustment of the sleeve 38. This adjustment may be made depending on the length of the 70 collar 38a or other work to be threaded. In this

form the cutter 16 may be held in position in the bar by means of the radial set screw 41. When the bar 12a is used the sleeve 20 will have to have an inside diameter corresponding to the outside diameter of the sleeve 38.

In other respects the embodiment illustrated in Figure 7 will be the same as that shown in other figures.

The drawings and description disclose what are now considered to be preferred forms of the 10 invention by way of illustration only, while the broad principle of the invention will be defined by the appended claims.

What I claim is:

1. A machine of the character described comprising a frame having end members provided with aligned bearings, a bar mounted for longitudinal movement in said bearings, a cutter on the bar, a sleeve between the end members threaded onto the bar, antifriction means for 20 confining the sleeve against endwise movement in the frame, means for rotating the sleeve relative to the bar to effect longitudinal adjustment of the bar.

2. A machine of the character described comprising a frame having end members provided with aligned bearings, a bar mounted for longitudinal movement in said bearings, a cutter on the bar, a sleeve between the end members threaded onto the bar, antifriction means for 30 confining the sleeve against endwise movement in the frame, means for rotating the sleeve relative to the bar to effect longitudinal adjustment of the bar, and means for taking up wear between the sleeve and bar.

3. A machine of the character described comprising a frame having end members provided with aligned bearings, a bar mounted for longitudinal movement in said bearing, a cutter on the bar, a rotatable member between the end 40 members and threaded onto the bar, means for confining said rotatable member against endwise movement in the frame, means for rotating said rotatable member relative to the bar to effect longitudinal adjustment of the bar.

4. A machine of the character described comprising a frame having end members provided with aligned bearings, a bar mounted for longitudinal movement in said bearings, a cutter on the bar, a clamp rod extended lengthwise 50 through the bar and clamping the cutter in place, a sleeve between the end members threaded onto the bar, antifriction means for confining the sleeve against endwise movement at the frame, means for rotating the sleeve relative to the bar to effect longitudinal adjustment of the bar.

5. A machine of the character described comprising a frame having end members provided with aligned bearings, a bar mounted for longitudinal movement in said bearings, a cutter on the bar, a sleeve between the end members threaded onto the bar, antifriction means for confining the sleeve against endwise movement in the frame, means for rotating the sleeve relative to the bar to effect longitudinal adjustment of the bar and means for preventing rotation of the bar relative to the frame.
